(57) **CLAIM**

The ornamental design for a golf club putter head, as shown and described.

DESCRIPTION

FIG. 1 is a front side view of the golf club putter head embodying my new design,

FIG. 2 is a rear side view of FIG. 1,

FIG. 3 is a left side view of FIG. 1,

FIG. 4 is a right side view of FIG. 1,

FIG. 5 is a top view of FIG. 1; and,

FIG. 6 is a bottom view of FIG. 1.

The broken line showing of a fragmented shaft is for illustrative purposes only and forms no part of the claimed design.
